GOLF CLUB

George M. Dick, 3063 Brighton Blvd.,
Denver, Colo. 80216

Filed Aug. 28, 1970, Ser. No. 24,742

Term of patent 14 years

Int. Cl. D21—02

U.S. Cl. D34—5

FIG. 1 is a perspective view of the golf club showing my new design, the opposite side being a mirror image thereof;

FIG. 2 is a rear view thereof with a portion of the handle broken away;

FIG. 3 is a front view thereof with a portion of the handle broken away;

FIG. 4 is a top view thereof with a portion of the handle broken away; and,

FIG. 5 is a side view thereof with a portion of the handle broken away, the opposite side being a mirror image thereof.

I claim:

The ornamental design for the golf club, as shown and described.
